UNITED STATES PATENT OFFICE.

WILLIAM F. COCHRANE, OF LA FAYETTE, INDIANA.

IMPROVEMENT IN HARVESTERS.

Specification forming part of Letters Patent No. 173,901, dated February 22, 1876; application filed March 27, 1874.

To all whom it may concern:

Be it known that I, WILLIAM F. COCHRANE, of La Fayette, in the county of Tippecanoe and State of Indiana, have invented certain new and useful Improvements in Grain-Harvesters; and I do hereby declare the following to be a full, clear, and exact description of the same, reference being had to the accompanying drawings, forming part of this specification, in which—

Figure 1 is a side elevation of the machine, with the cutting mechanism and inner drive-wheel removed. Fig. 2 is a top-plan view, and Fig. 3 is a detached view, showing the construction of the lifting-lever and the method of connecting it to the foot-board, and Fig. 4 is a detached view of the lever-bracket.

Similar letters of reference in the accompanying drawings denote the same parts.

My invention relates to that class of two-wheeled harvesting-machines, in which the main frame is formed with vertical segmental slots in the side pieces for the passage of the main axle, which acts as a rock-shaft, and allows the frame to rise and fall independently thereof, through the limits of the segmental slots.

It consists, first, in suspending the frame from the foot-board at the front and rear, in the first instance, by a lifting-lever and chain pivoted to the side of the foot-board in front of the counter-shaft, and in the second by a rising and falling bar projecting from the rear of the foot-board to a point over the axial line of the cutter-bar. This method of suspension enables the main frame to be raised and lowered by the lifting-lever, to elevate or depress the cutters and regulate the pitch of the guard-fingers at one and the same operation. The invention also consists in the construction of the lifting-lever, and the method of connecting it to the foot-board.

In the drawings, A is the main axle carrying the driving-wheels B, and C is the frame, the side pieces of which are formed with vertical segmental slots through which the axle passes. The frame is prevented from sliding laterally upon the axle by means of collars D fastened to the latter between the side

pieces of the frame, and these collars are cast with segmental pinions to mesh into curved racks cast in the segmental slots of the side pieces, for the purpose of raising and lowering the frame upon the axle when the lifting-lever E is operated. F is the foot-board supporting the draft-pole and driver's seat, and mounted upon the axle so as to project forward over the main frame. G is a bracket secured to the foot-board near the front inner corner, and formed with a guide-flange, H, and lateral boss I, the latter being provided with two eccentric recesses, j, in its edge. K is the lifting-lever fitted in a socket, L, which is cast with a grooved semicircular head, and a circular recess in one side. The lever-socket is pivoted to the bracket by a bolt, M, so that the boss shall enter the recess in the side of the socket, and serve as a bearing for the latter to turn upon, being guided by the flange H. N is a bolt, held within the lever-socket by a spring, so as to pass into the circular recess, and enter the eccentric openings in the boss, for the purpose of locking the lever in place. The outer end of the bolt is connected by a rod, O, to a latch, P, pivoted to the handle of the lever so as to be grasped by the operator. From the lifting-lever thus constructed, the front end of the main frame is suspended by an adjustable chain, Q, as shown. When it is desired to raise or lower the front end of the frame, the latch P of the lifting-lever is depressed to withdraw the locking-bolt from the eccentric recess in the boss, so that the lifting-lever may be turned thereon to the proper position. The spring-bolt is then released to again lock the lever to the boss. R is a hook pivoted to the rear edge of the foot-board, so as to extend backward over the main frame, where it is connected to a chain, S, attached to the rear edge of the frame, or to the shield of the pitman-shaft crank. The inner end of the hook is pivoted in a socket of the foot-board in such a manner as to prevent it from dropping down, while its outer end is free to rise above the plane of the foot-board. The hook and chain form the point of suspension for the rear end of the frame, and upon which it turns when its front end is

raised or lowered by the lifting-lever. T is the drag-bar jointed at its front end to the end of a girder, U, projecting laterally from the main frame in front of the inner driving-wheel, and V is the finger-bar bolted to the drag-bar shoe.

The front joint of the drag-bar is so formed as to enable the bar to rock freely, and to rise and fall at its rear end, carrying the finger and cutter bars with it, as well as the reel and reel-post.

Any of the ordinary joints now in use for this purpose may be employed, but I prefer the joint for which I have made application for Letter Patent.

The outer end of the finger-bar is supported by a grain-wheel, and provided with a grain-divider in the usual manner. The drag-bar is further connected to the frame by a back-brace, W, pivoted at one end to the drag-bar shoe in rear of the cutter-bar, and its opposite end to a projection, X, cast upon the crank-shield in line, or nearly so, with the pitman-shaft. The back-brace also forms a radius bar to equalize the throw of the cutters through the guard-fingers during the rising and falling movements of the cutting mechanism. Y is the extension-bar bolted firmly to the shoe of the drag-bar behind the cutter-bar, and extending inward behind the main frame, where it is connected by a chain, Z, with a bracket, A', extending upward and to the rear of the main frame at the inner corner thereof, as shown.

The front joint of the drag-bar and the bracket, chain, and extension-bar form the means by which the cutting mechanism is suspended from the main frame, while the frame is suspended from the foot-board by the lifting-lever, the lifting-hook, and their respective chains. The lifting-lever suspends the front end of the frame at the desired point, but the

rear end, owing to the flexibility of its connection with the foot-board, is allowed to rise freely with the cutting mechanism for passing over obstructions in the path of either. When the rear end is thus thrown upward, the pivoted hook also rises to prevent it from coming in contact with the shield of the crank or the pitman-shaft, and interfere with the free movements of the pitman and cutters.

By suspending the frame and cutting mechanism, as above described, the operation of the lifting-lever will elevate or depress the cutters, and at the same time regulate the pitch of the guard-fingers.

The height of the cutting mechanism with respect to the frame is adjusted by lengthening or shortening the chains of the extension-bar and pivoted hook.

Having thus fully described my invention, what I claim as new is—

1. The main gear-frame of a harvesting-machine adapted to rise and fall independently of and guided by the main axle, having its front end flexibly suspended from the foot-board or tongue-bracket by an adjustable lifting lever and chain, and its rear end suspended from the rear of the foot-board or tongue-bracket by a pivoted supporting arm and chain, substantially as described, for the purpose specified.

2. The lifting-lever L, having a grooved semicircular head, a circular recess on one side, and a spring-locking bolt, N, in combination with the bracket G, provided with a guide-flange, H, and lateral bars I, having eccentric recesses j j, substantially as described, and for the purpose set forth.

WM. F. COCHRANE.
